(57) CLAIM

We claim the ornamental design for a barrel cooker, as shown and described.

DESCRIPTION

FIG. 1 is a front perspective view of a barrel cooker showing our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a front perspective view of the bottom portion of the barrel cooker from which the upper barrel has been removed; and,

FIG. 9 is a top plan view of the bottom portion shown in FIG. 8.

The broken lines on the surface portion indicate contour and not surface decoration. The broken lines showing such features as hinges, handles and the like are not part of the claimed design.
